UNITED STATES PATENT OFFICE

WILLIAM F. SCHWEIGER, OF ROCHESTER, NEW YORK

MAIL-PRINTING MACHINE

Application filed February 23, 1924. Serial No. 694,702.

My present invention relates to printing machines and more particularly to machines of this kind adapted for the purpose of printing a postage mark upon mail matter under a 5 permit of the postal authorities and in lieu of the application of a separate stamp to the article and the invention has for its general object to provide a convenient, serviceable and compact machine of this nature having 10 improved means for safeguarding both the interests of the postal authorities and those of the owner of the machine. To these and other ends the invention resides in certain 15 improvements and combinations of parts all as will be hereinafter more fully described, the novel features being pointed out in the claims at the end of the specification.

In the drawings:

Figure 1 is a side elevation of a mail marking machine constructed in accordance with 20 and illustrating one embodiment of my invention, what may be termed the right side being shown.

Figure 2 is an elevation of the other or left 25 side of the machine.

Figure 3 is a top plan view.

Figure 4 is an enlarged fragmentary detail section on the line 4—4 of Figure 3.

Figure 5 is a bottom plan view.

Figure 6 is an end view.

Figure 7 is a detached view partly in section of a certain gear train and adjacent parts.

Figure 8 is an enlarged sectional view of 35 part of the envelope moistening mechanism taken on the line 8—8 of Figure 3.

Figure 9 is an enlarged view partly in section of the water pump and distributor.

Figure 10 is a top view of the moistening 40 device shown in side elevation in Figure 8.

Figure 11 is a bottom view thereof taken in the direction of the arrow in Figure 8.

Figure 12 is a sectional view on the line 45 12—12 of Figure 11.

Figure 13 is a fragmentary enlarged sectional view on the line 13—13 of Figure 3.

Figure 14 is an enlarged fragmentary section on the line 14—14 of Figure 3.

Figure 15 is an enlarged fragmentary section 50 on the line 15—15 of Figure 13.

Figure 16 is a view similar to Figure 15 with the parts in another position.

Figure 17 is a side view of the detachable printing unit carrying the type cylinder.

Figure 18 is an end view thereof.

Figure 19 is an elevation of the meter case, 55 detached.

Figure 20 is a section on the line 20—20 Figure 13 looking in the direction of the arrow.

Figure 21 is a section on the line 21—21 Figure 13.

Figure 22 is a section on the line 22—22 Figure 13.

Figure 23 is a section on the line 23—23 60 Figure 13.

Figure 24 is a vertical section taken through one of the parts shown in Figure 23 parallel to the plane of the latter figure.

Figure 25 is a section on the line 25—25 70 of Figure 13 looking in the direction of the arrow and in the opposite direction from that of Figure 20 in the same plane.

Figure 26 is a detail elevation of a removable type locking pin shown in Figure 25.

Figure 27 is a perspective view of a clutch shell in the mechanism of the printing unit.

Figure 28 is a fragmentary enlarged section 80 on the line 28—28 of Figure 25.

Figure 29 is an enlarged horizontal sectional view through the case of the meter mechanism showing the interior parts in top plan view and a fragment of the adjacent printing unit in central section.

Figure 30 is a fragmentary view similar 85 to Figure 29 with some parts removed and others in a different position.

Figure 31 is an enlarged vertical section through the meter mechanism taken in the plane of the counter worm.

Figure 32 is a detail view of an eccentric as 90 shown in Figure 31 but in another position.

Figure 33 is an elevation of a detail of one 95 of the counter mechanisms.

Figure 34 is a sectional view through the meter case similar to Figure 31 but with many of the parts removed to show a particular mechanism.

Figure 35 is a fragmentary sectional view 100

taken on the line 35—35 of Figure 31 showing the worm gearing of the counter mechanism.

Figure 36 is a perspective view of a certain cam actuator in the meter mechanism.

Figure 37 is a fragmentary view similar to Figure 31 but with parts removed to show features of the meter locking mechanism.

Figure 38 is a plan view of certain parts 10 of the meter locking mechanism located on the floor of the meter case.

Figure 39 is a view similar to Figure 38 but with the parts in another position assumed after the removal of the meter from the floor of the meter case.

Figure 40 is a fragmentary elevation of 15 locking mechanism for the counters located on the outside wall of the meter case.

Figure 41 is a side view of parts shown 20 in Figure 40.

Figure 42 is a view from the opposite side of the mechanism shown in Figure 40.

Figure 43 is a view similar to Figure 42 but with the parts in another position, the locking 25 position.

Figure 44 is a detail elevation of a detent lock.

Figure 45 is a section taken substantially on the line 45—45 of Figure 13.

Figure 46 is a view similar to Figure 45 but with parts removed and other parts in another position.

Similar reference numerals throughout the several views indicate the same parts.

In the present embodiment of my invention I have illustrated a machine that is adapted to receive a stack of envelopes and to feed them one at a time first through a sealing device and then between a printing couple that prints a date and a prepaid cancellation thereon. Connected with the printing couple is a counting and metering device that keeps track of the impressions made. This meter can be set for any desired number of cancellations and when this number is exhausted the machine is automatically locked against further operation. The meter is then removed and carried to the postal authorities who, upon payment of a corresponding sum of money reset the meter for the desired further number of cancellations. I refer to the impressions made by the printing couple as "cancellations" merely for convenience as they are not strictly stamp cancellations because no stamps are used but because they are made in the place and manner of a stamp cancellation though to indicate prepaid postage in lieu of a stamp.

When the meter has recorded the number 60 of cancellations that have been paid for, it not only locks the printing couple against further rotation but locks itself. Features of the invention relate to mechanism whereby the printing couple is driven through the 65 meter mechanism and the two elements are

mutually controlled by a key that is protected in such a way as to make duplication most difficult but the use of a duplicate key without detection impossible. Nevertheless, both the type cylinder and the meter mechanism are independently removable from the machine.

Referring more particularly to the drawings and principally to Figures 1, 3, 5 and 6 thereof, 1 indicates generally the frame of a table-like support having legs 2 and a top 3. At one end of the latter (and what may be termed the rear thereof) there is an opening 4 in the table top over which the stack of envelopes to be sealed and cancelled is placed being held between a rearward inclined gauge arm 5, a fixed lateral gauge plate 6 and an adjustable lateral gauge plate 7 the mounting of which will be hereinafter referred to. The gauge arm 5 is extended from an angular flat rod 8 slotted at 9 to receive a threaded post on which it is guided during adjustment and by which it is clamped in place through the use of a threaded clamp nut 10 thereon.

Beneath the forward end of the opening 4 and at one side thereof so that it comes approximately in the middle of the table is a pulley 11 over which passes a friction belt 12 in the nature of a rubber rope. The pulley 11 is an idle pulley but the belt also passes over a forwardly arranged driving pulley 13 on a main driving shaft 14 on the end of which is a large pulley 15 connected by a belt 16 with a pulley 17 on the shaft of a motor 19 mounted on the legs 2 at the rear of and beneath the table.

The upper reach of the friction belt 12 is partly above the surface of the table so that the bottom envelope of the pile rests in contact therewith and is picked up by the belt and conveyed forwardly while running against a guide rail 20 at the opposite side of the machine. Just forwardly of the opening 4 a portion of the surface of the table is constituted by a flap opening plate 21 the shape of which is clearly shown in Figures 3 and 5. Its rear edge 22 is both laterally inclined, running to a point, and beveled on its under side so it will catch the flap of an advancing envelope which has its folded edge against the guide 20 and spread it downwardly and outwardly. The envelope, during this operation, is held against both the conveying belt 12 and the plate 21 by an idler roll 23 the mounting of which will be later explained.

After passing the pressure roll 23 and traversing the plate 21 with its flap spread downwardly and outwardly to meet the latter the envelope, still under the frictional impelling force of the belt 12, passes beneath the sealing roll 24 and between it and a lower platen roll 25 fixed on the main driving shaft 14 against which the sealing roll runs.

The latter is an idler, the additional driving force required at this point in addition to the belt 12 being supplied by its companion roll 25 beneath. The sealing roll 24 is preferably of metal with the corrugated surface shown to insure a sealing contact at a plurality of points along the gummed edge of the flap while the platen roll 25 I prefer to make of a fairly hard rubber. It projects 5 slightly through an opening in a plate 26 arranged forwardly of the plate 21 and the rearward or adjoining edge of which is inclined downwardly as indicated at 27. Thus, as the flap of the envelope emerges gradually 10 and at a transverse angle from beneath the plate 21, it is folded up by the incline 27 against the body of the envelope and then drawn between the rollers to receive the sealing pressure.

20 The rollers 23 and 24 are partially related in their mounting being arranged to have a floating action adapting them to yield to envelopes of unusual thickness and to press uniformly upon the surfaces thereto. Fixed 25 in the vertical guide plate 20 at the left side of the machine is a shaft 28 secured by a nut 29 which shaft extends across and above the path of the envelope its free end being on the opposite side of the plate 21 and the 30 belt 12. This free end extends through a slot 30 in a rock arm 31. Spanning the rock arm at this point is a bifurcated cylindrical casing 32 fixed on the shaft 28. It is bored out centrally to receive a sliding plunger or 35 bearing member 33 behind which is a spring 34 beneath a cap 35. The arm 31 is thus mounted for a joint pivotal and vertical bodily movement that gives it a free floating action, the upward movement being yielding 40 against the spring 34.

At its rear end, the arm 31 carries the roller 23 on a stud shaft 36 fixed in the arm. The shaft extends through the latter and its projecting portion is flattened or faced at 45 37 and carries a sliding collar 38 having a set screw 39 by which it may be secured at different points. A fixed arm 40 on the collar carries the lateral gauge plate 7 for the stack of envelopes before referred to. Also 50 carried at the rear end of the arm 31 is a fixed shoe 41 having a forwardly and downwardly inclined tip that rides on the carrier belt 12. This shoe is fixed to the arm. Just forwardly of it is a similar shoe 42 pivoted 55 on a stud 43 on the arm 31. Its tip is bifurcated and it is pressed downwardly to straddle the belt by a spring 44 on the stud. These two shoes between them prevent more than one envelope from passing under the roll 23 60 at one time.

The sealing roll 24 is mounted on the arm 31 at its opposite or forward end on a stud shaft 45 secured to the arm by a nut 46. The said stud shaft and roller raise and lower 65 with this end of the arm but the opposite

end of the stud shaft 45 is connected by a link 47 with the fixed stud shaft 28 on both of which it is pivoted. The arm 47 is pressed downwardly to carry the shaft 45 downwardly and hold the roll 24 against its work by a spring 48 coiled about the shaft 28 and bearing on the link 47.

The result of these arrangements is that as an envelope passes under the roll 23 and it rises, it raises the rear end of the arm 31 70 on the shaft 45 as a fulcrum against the resistance of the plunger 33. Correspondingly, the sealing roll 24, as the envelope passes beneath it, may raise the forward end of the arm 31 with the shaft 36 as a fulcrum. 75 With envelopes of the same or different thicknesses beneath both rollers the arm 31 is raised bodily at both ends and equalizes itself with its additional pivotal movement.

Flap moistening mechanism

As the flap of the envelope is passed beneath the plate 21 by the inclined edge 22 thereof it is brought in contact with moistening devices which apply a film of water to the gummed portion which devices are shown in detail in Figures 8 to 12. Below the plate 21 is an inclined block or metal casting 71 secured thereto at 49. At its rearward portion it is bored from the lower edge to form 75 two parallel longitudinal wells 50 and 51 connected at their upper ends as indicated at 52 and plugged at their lower ends by screws 53. The well 51 is intersected by a narrow slot 54 opening on the under face of 80 the block. Next forwardly to this slot is a parallel groove 55 and beyond that a body of felt or similar absorbent and brushing material 56 suitably secured to the face of the block.

A detachable water tank 57 is hung beneath the table on hooks 58 engaging pins 59 on the frame 1 (Figures 1 and 2). Depending into it from a bracket plate 60 on the frame 1 is an ordinary force pump 61 85 the piston of which is shown at 62 connected by a crank 63 with an eccentric 64 on the drive shaft 14 by which it is operated. The intake is at 65 and the pump discharges through a pipe 66 through a suitable valve 90 the casing of which is indicated at 67 and the discharge from which is indicated at 68. A by-pass 69 leads from the casing back to the bottom of the tank and by operating the valve handle 70 (Figures 5 and 9) the 95 volume of water pumped through pipe 68 can be increased or diminished. When diminished the pressure built up in the valve is reduced through the by-pass 69 and the water returned to the tank.

The discharge pipe 68 leads into the block 71 near the bottom thereof and communicates with the lower portion of the well 50 which is filled thereby. It is driven over through the connection 52 to the well 51 from which it es- 100

apses in a sheet through the slot 54. As the downwardly angled flap of the envelope reaches the block 71 it is caught by an outstanding guard 72 in the form of a wire yoke having eyes at the lower ends of its arms secured to the block by screws 73. This guard causes the flap to engage the face of the block. The portion of the latter containing the slot 54 is angularly arranged as shown in Figure 10 12 so that the flap comes in contact with it first and receives a film of water from the slot. It next brushes against the felt 56 which removes the excess of water and wipes it evenly over the gummed surface. After being thus 15 moistened the envelope finally reaches the plate 26, the flap passing out from beneath the plate 21 and being folded upwardly against the body of the envelope by the incline 27 and the sealing roll 24 as previously 20 described.

The printing mechanism

From the plate 26 the sealed envelope passes into the printing couple to receive its 25 imprint or cancellation in the upper right hand corner. Referring more particularly to Figures 1, 6, 7, 13 and 14, this printing couple embodies a type cylinder 74 and a printing cylinder 75 the point of printing contact between which is slightly above the level of the table and the previous path of the envelope. The printing roll 75 is carried on a shaft 76 to which a hub 77 of the roller is pinned at 78 and which turns in bearings 79 in the opposite arms of a yoke 80 (Figure 13) which yoke is pivoted to swing on the drive shaft 14 as shown in dotted lines in Figure 14. The yoke extends forwardly far enough to support the printing roll in an overhanging position 40 beyond the forward end of the table and the inner arm thereof is curved downwardly to clear the end rail of the table frame 1. Also pinned at 81 by its hub 82 to the shaft 76 is a rubber feed roll 83 cooperating with an 45 upper feed roll 84 to positively feed the envelope while it is being printed.

Below the overhanging portion of the yoke 80 at the forward end of the table is a bracket 85 having two tubular guides 86 rising therefrom and containing supporting posts 87 (Figure 14) adapted to slide vertically therein. The posts rest upon springs 88 coiled about reduced portions 89 thereof and acting against adjacent shoulders and the bottoms of 55 the guides, respectively, so that the posts are resilient. They bear at their upper ends against inturned flanges 90 on the yoke 80 and, the compression springs 88 being normally flexed, they apply an upward pressure on 60 the yoke that holds the feed roll 83 in contact with its companion roll 84 and the printing roll 75 in contact with the type roll 74, at least when the type is at the printing point.

The printing cylinder and the feed roll 84 65 adjacent to it are removable as a unit from the

machine as will be hereinafter described and to permit such a removal it is necessary to lower the printing roll 75 and the feed roll 83 out of contact. I therefore provide the swinging yoke 80 as a mount for these parts and also means for holding it depressed while the printing couple is being manipulated. To this end the reduced portion 89 of each post 87 extends through the bottom of the guide and terminates in a head 91 on the under side of the bracket 85. Referring to Figures 5 and 6, a slotted latch plate 92 is guided on headed pins 93 on the under side of the bracket and its wings are provided with downwardly turned lugs 94 (see also Figure 1). When the yoke 80 is depressed to lower the rolls 75 and 83, the latch plate 92 is drawn forwardly by means of a finger piece 95 and the lug 94 engage beneath the heads 91 thereby holding the springs 88 compressed and the posts retracted.

As before mentioned the printing element including the type cylinders 74 is independently detachable from the machine. Referring more particularly to Figure 13, there is secured to a portion of the frame 1 by screws 96 a casting 97 constituting a socket member having a circular socket 98 therein provided with a locking pin 99. In this socket is fitted a type casing 100 suitably grooved at its inner ends to form a bayonet joint with the locking pin 99, the casing being inserted with a combined longitudinal and rotary motion. The casing 100 is in the form of a shell that is cylindrical and open on its under side. To its outer end is secured a bearing member 101, and there is also an intermediate bearing member 102. Turning in these bearings is a shaft 103 to which the type cylinder 74 is pinned at 104, and on which the feed roll 84 turns freely as driven by the feed roll 83. This feed roll 84 is hollow and in its interior is a quantity of absorbent material 105 that is saturated with oil which seeps through openings 106 in the bearing hub 107 on which the roll turns and lubricates the shaft.

Centrally arranged in the inner end or butt of the shell or casing is a lock cylinder 108 with spring pressed tumblers 109 in the manner of an ordinary Yale lock and adapted to be controlled by a key of that nature to be hereinafter referred to. The end of the cylinder has an enlargement 109^a on an end projecting into the shell on which enlargement is a transverse key 110 that interlocks the cylinder with the slotted end 111 of shaft 103 so the latter is adapted to be driven through the lock cylinder or vice versa. Splined to the shaft 103 at 112 is an inner clutch element 113 cooperating with an outer clutch element 114 that has a direct bearing in the shell as shown. These clutch elements will be later described in detail, the present object being to explain that 114 is the driving clutch member which through the inner clutch member 113 turns the 115 120 125 130

shaft 103 carrying the type cylinder, and this outer clutch member 114 has secured to its face a gear ring 115 from which the power is transmitted from the main driving shaft 14 of the machine through gearing that will now be described.

Referring additionally to Figure 7, a gear 116 is carried on the drive shaft 14 and meshes with two intermediate gears 117 and 118 the latter of which in turn, meshes with the ring gear 115 of the printing element so that the ring gear is driven positively from the main drive shaft. It is necessary, however, to disconnect this gearing when the printing element is removed from the machine for which purpose the intermediate gear 118 is mounted on a swinging arm 119 turning on a stud 120 on which its companion gear 117 is mounted. This arm is adapted to swing from the full line operative position of Figure 7 to the dotted line position carrying the gear 118 free of the printing mechanism. When in operative position, the arm 119 is held fast by a thumb screw 121 threaded in the plate 122 through which it projects to engage the arm.

It may be here stated that the plate 122 which is clearly shown in Figure 7 in its outline is the mounting plate for the gearing just described, for the printing unit and for the meter mechanism to be later described. It is offset from the right side of the machine (Figures 5 and 6) and supported by studs 123 from the side rail of the table frame 1.

At the end of the shaft 76 of the printing roll 75 is secured a gear 124 which turns close against the mounting plate 122 as does the end of the shaft itself. This gear is also driven from the gear 116 on the driving shaft through an intermediate gear 125 so that the printing cylinder is positively driven as well as the feed roll 83 on the same shaft with it.

An inking roll 126 contacts with the printing cylinder 74 through an opening 127 in the shell 100. This inking roll also has to be displaced during the removal of the printing cylinder and it is mounted accordingly. In the present instance it is carried on a shaft 128 between two arms 129 on a yoke 130 having an extension 131 constituting the operating handle when required. The yoke is pivoted to a stud 132 on the swinging plate 119 so that it may swing with the latter as the printing cylinder is thrown out of gear to gain access to the type through the opening 127 for cleaning or other purposes.

When the printing cylinder is to be removed, the inking roll is simply slipped off of the stud 132 in a lateral direction that is, the same direction in which the type cylinder is removed. To permit of this free detachment, a tensioning device is provided for the ink roll that acts upon it but is not connected to it. It consists in the present instance of a slotted plate 133 guided on headed pins 134 on the swinging plate 119. An extension coil

spring 135 connected to one of the guide pins and to a pin 136 on the slide holds a flanged portion 137 on the latter against the end of the yoke 130 to maintain the inking roll against the cylinder in a manner that will be clear from an inspection of Figure 14. The end of the flange 137 is curved to facilitate the attachment and removal of the yoke.

With the inking roll removed and the plate 119 thrown back to disconnect the gearing, the printing cylinder including the whole unit contained within the shell 100 is removable in an endwise direction by releasing a detaining screw 138 that engages it through the top of the fixed socket member 97, which release of course is followed by a rotative motion to disengage the bayonet joint furnished by the pin 99. When the unit is removed it parts from the associated mechanism (Figure 13) on a line in the plane that comprises the inner end face of the shell 100 and that of the lock cylinder 108 the key hole in which is exposed. The head 109 of the lock cylinder remains in engagement at 110 with the slot 111 in the end of shaft 103. The type cylinder shell unit is shown detached in Figures 17 and 18 which compare with Figure 13.

For reasons that will later appear, the machine has a definite cycle of movement comprising one revolution of the type wheel and the type or plate thereon always stops in register with the opening 127 in the shell 100 as shown in Figure 17. Of course the form of this may be varied but it preferably comprises a plate 139 having a circular device bearing the name of the post office at the place of issue. This is secured by screws 140 to a block 141 (Figures 21 and 25) that is dove-tailed into the body of the cylinder 74 as shown. It is inserted or withdrawn from the outer end face of the latter and is normally secured in place by the head of a screw 142 but the proximity of the feed roll 84 prevents it from being removed except by dismantling the whole type cylinder unit for the reason that prepaid postage once issued from one post office should not be used through any other. At this point it may be explained that the shell 100 and its interior parts are held together by blind screws or the unit is otherwise sealed so that it cannot be taken apart or modified except at the factory without detection. Further reasons for this shall appear later on.

Within the plate 139 are a plurality of small types indicated generally at 143 which respectively carry for instance the month, day, hour and year and these of course have to be changed at least once or twice a day. They are therefore held in a releasable manner. They occupy a squared opening in the plate 141 and their lateral faces in abutment with the walls of said opening are, jointly with such walls, intersected longitudinally by bores 144 in which are arranged rotatable

pins 145 that lock the types 143 to the type plate 141. One of these pins is shown in detail in Figure 26. Their outer ends project beyond the end face of the type cylinder 74 and are provided with eyes or sockets 146 to receive a suitable instrument by means of which they may be turned. When turned a quarter turn, cut away or semi-cylindrical intermediate portions 147 thereof opposite to the types 143 permit these to be withdrawn and replaced with others.

Referring to the previously described clutch elements 113 and 114, a transverse section through these is shown in Figure 22. The inner clutch element 113 is provided with the usual tapered pockets 148 in which are rollers 149 the tendency of which is to move to the small end of the pocket and jam with the surface of the outer clutch element 114 under the influence of springs 150. Thus, with the outer clutch the guiding element carrying the gear 115, the tendency is normally for the clutch to operate and drive the shaft 103 but there is a clutch controlling element 151 turning loosely on shaft 103 inside of the outer clutch element 114 and interposed between the two clutch elements except for openings 152 that are occupied by the rollers 149. A perspective detail of this clutch controlling member is shown in Figure 27. The springs 150 normally operate the rollers 149 to hold them in operative position but it will be seen from an inspection of Figure 22 that a counter clockwise movement of the controller will unseat the rollers and disconnect the clutch elements from each other.

The controller 151 has a hub 153 thereon the end of which is transversely slotted at 154 to form a coupling element. This extends into the central opening of a disk 155 also loose on the shaft 103 and running against the head 109^a of lock cylinder 108 and lugs 156 projecting into the opening interlock the disk with the controller so that they are practically one piece for all purposes and are made in this manner only for convenience in assembling. A peripheral groove 157 on the controller disk divides it into two flanged parts between which are pivoted two spring pressed latch members 158 and 159. On the flange that is toward the type cylinder is a stop shoulder 160 while on the other flange are provided stop shoulders 161 and 162. Normally the stop shoulder 161 abuts the portion 163 of a sliding pin 164, as shown in Figure 23 and also in Figure 15, that is this is the point from which a cycle of the machine starts and the point at which it is stopped by such engagement which halts the controller 151, thereby throwing out the clutch 113—114 through which the type cylinder is driven.

The underlying purpose of the mechanism now being described is two-fold, namely,

first to exercise a control over the driving of the type cylinder by the meter mechanism hereinafter described, and second, to provide means whereby the printing mechanism will be inextricably locked in case this mechanism is tampered with and require the services of expert and authorized persons to restore it to working conditions. In other words, each impression from the type cylinder meaning the expenditure of a postal fee, and the machine being set for a definite number of impressions in accordance with the money deposited, each revolution of the type cylinder must be recorded in the meter mechanism, and when this is removed in the manner hereinafter explained and a dishonest person attempts to otherwise control the printing mechanism he will not only be prevented from successfully doing so, but his attempt will be revealed by the disarrangement of the machine and the necessity of resorting to the postal authorities in order to restore it.

With this in mind and returning to Figures 13, 20 to 28, and additionally to Figures 15 and 16, the pin 164 is guided in the inner end of the type cylinder shell 100 at one side of the lock cylinder 108 which occupies the same enlarged or heavy end portion of the shell. It is retained behind a plug or bushing 165 in which a reduced portion 166 of the pin is guided and through which it projects so that its end is exposed substantially flush with the end face of the shell. The bushing 165 is locked by a set screw 167, the head of which is faced off so that it will be inoperative and indistinguishable on the surface of the shell. At its opposite end the pin 164 is pressed against endwise by a spring plunger 168 operating in a socket 169 in the shell 100 so that the pin is normally projected toward the end of the shell to occupy the position shown in Figures 23 and 15.

The portion 163 of the pin previously referred to is in the form of a circular flange near the inner end, and at the inner end is another similar flange or abutment 170. This is adapted to be engaged by a stop shoulder 160 on the disk 155 in the same manner that flange abutment 163 may be engaged by a stop shoulder 161 and stop shoulder 162. The spacing between the abutments 163 and 170 is such however that when one is in engaging position the other is out, that is they alternate in the paths of their respective stop shoulders.

Assuming that the parts are in the normal position of Figures 15, 23 and 24, the outer driven clutch member 114 is prevented from locking with the inner clutch member 113 due to the fact that the rollers 149 are held against jamming by the controller 153 and the latter cannot be moved because stop 161 on the controller disk 155 is in engagement with abutment 163 of the pin 164. When this

pin is moved endwise against the tension of spring 169 in a definite timed relationship through instrumentalities connected with the meter mechanism hereinafter described, stop 161 is released from abutment 163 on the pin and abutment 170 goes into the path of stop 160. If pin 164 is then prematurely released the stop 162 will engage abutment 163, halt the controller 153 and throw out the clutch before the printing cycle has been completed. Not only this but latch 159 will lock against abutment 163 on the pin and prevent it from being actuated again to release itself from stop 162 and permit the remainder of the revolution to be performed until authorized experts have restored the mechanism. Similarly, if pin 164 is pressed inwardly too long, abutment 170 thereon will engage stop 160 and throw out the clutch before stop 161 has returned to initial position to do so and abutment 170 will also be locked against restoration of pin 164 by latch 158.

It will be seen from this that it is highly improbable that a person tampering with the machine in an effort to manually release the pin 164 and then restore it with such timing as is provided by the meter mechanism to permit a cycle of the printing mechanism would not be thwarted in his endeavor and with the result that he would be compelled to leave the machine in such condition that it would bear evidence of the attempt.

Means are also provided for preventing retrograde movement of the type cylinder 74 either for the purpose of running an envelope through backwards or for the purpose of releasing stops 160 or 162 from engagement with the pin 164. This means comprises in the present instance a ratchet pin 171 shown in detail in Figure 28 and which is mounted to slide in a bushing 172 in the end of the type cylinder, it being pressed outwardly by a spring 173 in a cavity behind it. Secured by a set screw 174 (Figures 13 and 20) to the bearing sleeve 107 of the shell piece 101 is a ratchet 175 having lateral teeth of the nature shown in Figure 20 and the engaging faces of which are indicated at 176, 177 and 178. These teeth are so arranged that they correspond to the positions of stops 160, 161 and 162 and prevent the type cylinder shaft 103 from being reversed when any one of these stops is in engagement with pin 164.

Meter mechanism

Before going into the details of the meter construction I will give a general idea of its external characteristics, its functions and the manner in which it is manipulated. Referring for instance to Figures 2, 3, 6 and 13, the meter embodies in general a box like metal casing 179 that rests on a bracket 180 secured to the frame plate 122 so that the meter occupies an offset position at one side of the machine but in alignment with the

printing unit contained within the shell 100. Viewable from its exterior are four registers 181, 182, 183 and 184 the first of which is a descending register that is set by the postal authorities for the total of postage that is bought. Register 182 operates in conjunction with register 181 but is graduated finer to give more accurate readings. Register 183 is a totalizer that shows the aggregate cancellations made by the machine over any desired period with or without reciting while 184 is a day counter that simply gives the cancellations during a day of operation being reset at will by a knob 185 freely accessible on the exterior. The other registers may be reached only by authorized persons being surrounded with certain safeguards herein-after described. When the number of cancellations for which the meter has been set have been exhausted, the meter automatically locks itself and in so doing locks the printing mechanism inasmuch as the latter can be turned only through the medium of the meter. At this point the meter is lifted off of its bracket and taken to the postoffice where it is unlocked by means of a lock shown at 186 and reset by means of a crank 187 (shown in dotted lines in Figure 3) inserted at 188. Certain locking and releasing operations are automatically performed by the acts of removing the meter from or applying it to its bracket so that neither the meter nor the printing unit can be turned except in a prescribed manner when they are disassociated.

To facilitate the removal and transportation of the meter which is relatively heavy, it is provided with a pivoted bail-like handle 189 the arms 190 of which respectively turn on projecting bearing sleeves 191 and 192 secured in opposite walls of the casing 179. Referring to Figures 2, 13 and 19 an extension 193 of one arm 190 rests against the stop pin 194 on one side of the meter casing and a positioning pin 195 on an adjacent ear 196 struck up from the edge of the bracket 180 while on the other arm 190 of the handle is a similar hook extension 197 that cooperates with a stud 198 projecting outwardly from the plate 122 to which it is fixed. A shoulder 199 on the inner arm of the handle cooperates with a stop 200 on the meter case to limit the upward movement of the handle to operative position. The latter is shown in Figure 19 and the folded position in Figure 2.

Turning in the bearings 191 and 192 is a shaft 201 which also has a sliding endwise movement. It is articulated at 202 and terminates at its outer end in a handle 203 so that the shaft may be partially withdrawn and the handle dropped to a position parallel with the wall of the casing for which purpose the bearing sleeve 191 is notched at 204. The normal position is shown in Figures 6 and 13; the retracting movement by dotted lines in Figure 3 and the final withdrawn position

in Figure 4. The inner end of the shaft 201 is bifurcated to receive the shank of a key 205 (Figures 4, 13 and 15) that is adapted to fit the lock cylinder 108 on the printing unit and through the medium of which shaft 201 of the meter is driven by shaft 103. This key is preferably pivoted at 206 to the shaft so that it will readily enter in and withdraw from the lock cylinder when the meter is applied or removed.

The arrangements are such that, once the shaft 201 is pulled out, the key 205 withdrawn from the lock cylinder 108 and the meter removed, the shaft is locked in this position and can neither be rotated nor restored to normal position. Its rotation is prevented because by this means the meter reading might be altered. Its sliding movement is prevented in order to keep the key 205 obscured and inaccessible for the purpose of duplicating it. It is contemplated that a dishonest person might attempt to provide himself with a similar key when for instance he is sent to the post office with the meter to have it reset. For this purpose there is provided on the shaft 201 between it and its bearing 192 a sleeve 207 in which the key slidably operates through a slot 208 in the end thereof that is otherwise closed. The key retracts from the lock through this slot and is completely housed while the meter is detached so that inspection of it is impossible.

Projection of the key 205 to an exposed position through a return movement of the shaft 201 until the meter is again applied to the machine in abutment with the end of the printing element is prevented by the following mechanism:

A shaft 201 is provided with a circumferential groove 209, a circumferential groove 210 and diametrically opposed grooves 211 connecting the circumferential grooves as shown in Figures 13, 31 and 37. Normally, or when the meter is in cooperation with the printing movement, these longitudinal grooves 211 are in the position shown in Figures 13 and 31. Mounted to turn loosely on the shaft 201 is a sleeve 212 having a flange portion 213 having a pair of inwardly projecting diametrically opposite pins 214 that normally occupy the groove 209 when the parts are in the position of Figure 13. This of course permits rotation of the shaft 201 while being driven from the shaft 103 through the key 205. As before described these shafts stop always in the same position after one rotation on a cycle of the machine and at this point the pins 214 are in alignment with the grooves 211 so that they do not interfere with the endwise movement of shaft 201 and the withdrawal of the key from the printing unit.

When the shaft is so moved endwise and the key withdrawn, the pins 214 emerge from

the slots 211 and occupy the other circumferential groove 210. Fastened to the flange 213 of collar 212 is a slotted arm 215 (Figures 31 and 37). A pin 216 on a lever 217 occupies the slot in the arm and the lever is pivoted at 218 to a bracket 219 secured to the inside of the meter casing. On the opposite side of the pivot an arm 220 on the lever comes in alignment with an opening 221 through a bushing 222 in the bottom of the meter case. When the meter is in place on the bracket 180, a key pin 223 extending upwardly from the bracket and having a peculiarly shaped upper end 224 receives this arm 220 and holds it in an elevated position depressing the lever 217 as shown in Figure 31 against the tension of a spring 225 connected to it and to a fixed arm 226 on the supporting bracket 219. This depression of the lever 217 holds the arm 215 down and the collar 212 with the pins 214 thereon in the position heretofore described in alignment with the grooves 211 in the shaft 201 permitting the latter to be moved endwise.

When the meter is removed from the machine however, the key pin 223 is of course withdrawn so that the spring 225 reverses the lever 217 and rotates the pins 214 to the position of Figure 37. The key 205, having necessarily been withdrawn, the pins 214 rotate in the circumferential groove 210 into positions out of alignment with the longitudinal grooves 211 so that the key cannot be again projected until the meter is placed back on the machine and it enters the printing element.

There is another upstanding pin 227 on the bracket 180 that projects through an opening in another bushing 228 in the bottom of the meter case but this is merely a centering pin to help position the case.

To prevent anyone from inserting an instrument through the opening 221 when the meter is removed and duplicating the function of the key pin 223 I provide a masking bolt 229 to cover the opening 221 and lock the arm 220 in its lowered position. Referring to Figures 38 and 39, the first of which shows the positions of the parts with the meter in place on the machine and the latter with it removed, this bolt 229 consists of a lever pivoted at 230 to the bottom of the case on one side of the opening 221 and pivoted at 231 on the other side to a sliding plate 232 slotted and guided beneath a headed pin 233. On the lever 229 is an offset finger 234 while the lever arm 220 is provided with a pin 235. As soon as the key pin 223 is withdrawn, a spring 236 connected to the slide 232 and to a fixed bracket 237 on the bottom of the case pulls the lever 229 over so that the finger 234 locks over the pin 235 and holds the lever depressed. At the same time an opening 238 in the lever 229 is carried out of alignment with the opening 221 and obstructs it. The

key pin 223 upon reentering the casing and because of the inclined portion shown on its end 224 thrusts back the plate 229 and releases the pin 235 raising the lever arm 220 to just the right point to unlock the key shaft 201 for endwise movement and even if the member 229 were otherwise dislodged the operator would not know how far to raise and halt the arm 220 in order to release the meter key.

It is now necessary to refer to Figures 15 and 16 and the mechanism there previously described as requiring a properly timed release in order to drive the shaft 103 a complete cycle through the clutch mechanism thereof. Recalling that the locking pin 164 must be thrust inwardly and then retracted at just the proper points in the rotation of the type cylinder shaft, there is arranged for this purpose in the inner wall of the meter case 179 a barrel 239 in which is guided a longitudinally movable push pin 240 having a reduced end 241 projecting exteriorly in alignment with the locking pin 164. A finger 242 on a shipping lever 243 pivoted at 244 (Figure 34) to a bracket 245 has a tendency to project the push pin 240 being engaged between the shoulders 246 and 247 on the latter and its opposite end being provided with a spring push button 248 that bears against the wall of the casing and is normally compressed. There is also, however, a detent 249 engaging between shoulder 247 and a shoulder 250 on the push pin so that it is locked retracted in the position of Figure 15. This detent is shown in Figure 34 to comprise a downwardly extending arm on a bell crank lever 251 pivoted at 252 to the casing. It may be referred to as the principal locking element, in a way, between the meter mechanism with its function of releasing the printing mechanism for each cycle of operation and the rest of the machine. It is released by the passage of the envelope into the printing couple and in the following manner:

Referring to Figures 13, 14 and 31 there is arranged in the path of the envelope A as it emerges from between the sealing rolls 24 and 25 a trip 253 in the nature of a vertical plate having a rounded or cam shaped upper edge. It is carried on the end of a plunger 254 slideable in a tubular guide 255 pivoted near its opposite end at 256. The plunger has a flattened side 257 engaged by a set screw 258 to prevent it from turning and behind it is a spring 259 that tends to hold the plunger projected. As an envelope A strikes the plunger it is held to the bed of the machine by a presser foot 260 and after thrusting the trip plate before it for a distance it rides over the same and into the bite of the printing couple after which the plunger and trip plate are thrust outwardly again by the spring 259.

When so actuated by the envelope the trip plate engages an upstanding arm of a bell

crank lever 261 pivoted at 262 to a bracket on the frame and to the other arm of which lever is pivoted at 263 a link 264. The link 264 is pivoted at 265 to a dog 266 fixed on a shaft 267 journaled to a long bearing sleeve 268 that is fastened in a bushing 269 in the frame plate 122 by a set screw 270. The opposite end of the shaft 267 has fixed to it an arm 271 pivoted at 272 to a link 273 that in turn is pivoted at 274 to a vertical push rod 275. This push rod is slotted and guided on a headed pin 276 mounted in and projecting quite a distance from the wall portion of the bracket 180. Its upper end is guided in a slot 277 in the horizontal portion of the bracket 180 and the bottom of the meter casing. A box or casing 288 surrounds the arm 271 and push rod being secured to the bracket 180 by flanges 289 and in the normal position said mechanism is disposed as in Figure 31.

When the envelope actuates the trip plate 253, this system of levers causes the push rod 275 to be thrust upwardly from the position of Figure 31 through the floor of the meter case to the position of Figure 34. In so doing, (see also Figures 37, 38 and 39) it engages a foot 290 on a lever 291 pivoted at 292 to the inside wall of the meter case. This lever is normally held down by a spring 293 and when raised a pin 294 thereon that normally rests against a shoulder 295 on a link 296 as shown in Figure 31 first raises said link and then slips off of the shoulder as shown in Figure 34. The link 296 is a floating link and is normally held against the pin 294 by a spring 297 while its upper end is pivoted at 298 to the previously described bell crank lever 251 having the detent arm 249. The result is that the detent 249 (Figures 15 and 16) is moved out of locking engagement with the shoulders of the push pin 240 and the latter is free to actuate the locking pin 164 of the printing couple when the shipping finger 242 is moved in the manner about to be described.

When the meter is removed from the machine and the slide bar 232 locks the lever 217 and obstructs the key pin aperture 21 it also locks lever 291 through the medium of a flanged projection 299 that engages over the foot 290 of that lever as shown in Figures 37 and 39. It is thus impossible to duplicate the functions of the push rod 275 by poking an instrument through aperture 277.

The push pin 240 of the meter mechanism being released in the manner just described by the passage of an envelope into the printing element, the next movement required to unlock the printing clutch controller 155 through release of the locking pin 164 is actuation of the said pin 240 which, as before stated, is accomplished automatically through the force of the spring push button 248 of the shipper. The clutch elements 113

and 114 go into engagement and both of the shafts 103 and 201 start to revolve, one through the other, driving the printing couple. On the sleeve 207 containing the slot 208 (Figure 36) through which the meter shaft is key driven is a cam disk 300 having a cam faced lug 301. This lug normally rests against a projecting end 302 of push pin 240 as shown in Figures 15 and 34. With the movement of the pin the cam lug travels from that position through approximately two-thirds of a revolution and strikes a roller 303 on shipper lever 243 rocking the lever to compress its spring and causing the push pin 240 to be restored to normal position. At this time the trip 253 is released through the passage of the envelope between the printing rolls and the push rod 273 is lowered (Figures 31 and 34) restoring link 296 and allowing 20 detent 249 to lock the push pin.

Locking pin 164 (Figure 15) restores itself under the influence of its own spring 169 and the described two-thirds revolution of the cam lug 301 from the push pin projection 302 to the shipper roller 303 is so coordinated with the clutch controller 155 that the stops thereon avoid the stop shoulders 163 and 170 on the stop pin 164 and a complete revolution of the controller is permitted at the end of 30 which the clutch is thrown out as previously described. Upon the completion of the cycle, the cam lug 301 returns to contact with the push pin projection 302 by which it is locked as shown in Figures 15 and 37.

Registers and counters

The number, nature and arrangement of the various registers and counters of the meter mechanism has been previously described in a general way. They are all driven from the meter shaft 201 in the following manner:

On the end of sleeve 207 is a cam 304 in the nature of an eccentric (Figures 13, 31 and 34) embraced by a yoke or strap 305 pivoted at 306 to a bracket 307 offset from the wall of the casing 179. To the arm 308 of this eccentric strap is pivoted at 309 a link 310 pivoted at 311 to a ratchet arm 312 on the operating shaft 313 of the day counter 184 the details of which are not shown inasmuch as it is only a simple register reset at pleasure as heretofore described. Another link 314 also pivoted to the strap arm at 309 and extending in the opposite direction is pivoted at 315 (Figures 31 and 34) to a yoke lever 316 swinging loosely on a transverse shaft 317 on which is a ratchet wheel 318. Between the arms of the said lever 316 there turns on pivot 315 a pawl 319 actuated by a spring 320. Another pawl 321 pivoted at 322 and actuated by a spring 323 cooperates with the ratchet to prevent retrograde movement. 60 Thus, at each cycle of the machine upon a

rotation of shaft 201 the pawl 319 communicates a turning impulse to a shaft 317.

Referring more particularly to Figures 29, 30, 31 and 35, the shaft 317 carries a worm 324 meshing with a worm gear 325 loose on a shaft 326 extending longitudinally of the meter case and having bearings in bushings 327 and 328 in the walls thereof. A hub 329 on the worm gear 325 carries a clutch pin 330 with which cooperates a castellated clutch collar 331 having a peripheral groove 332 engaged by a yoke shaped shipping arm 333 adapted to throw the clutch out at certain times in the manner and for the purposes hereinafter described. Normally, however, the clutch elements are in engagement and the shaft 326 is ready to be rotated by the worm 325 through the clutch element 331 which is splined thereto at 334 to slide into and out of engagement with the clutch pin 330.

At the opposite end of shaft 326 is the register wheel 182 which may be termed the primary register inasmuch as it is directly driven by the shaft 326 to which a hub plate 335 is pinned at 336 and because it is graduated to registered cancellations from one to a thousand on a descending scale. Each impulse communicated to the worm shaft 317 from the main meter shaft 201 turns shaft 326 sufficiently to register a reading of one less cancellation on wheel 182. An indicator is provided at 337 viewable through a window 338 in the top of the meter casing.

The secondary register 181 is a similar wheel but is graduated in thousands up to a hundred thousand and is driven concurrently with the primary register 182. It is mounted (Figure 13) on a hub 339 turning on bushing 191 and is interlocked with a gear 340 turning freely on shaft 201 between said bushing and the collar 212. The shaft 326 is threaded throughout its intermediate portion to constitute a lead screw of very fine pitch on which travels a nut 341 provided with a roller 342 travelling on the top wall 343 of the meter case. On the under side of the nut is secured a rack 344 meshing with gear 340. As the shaft 326 is intermittently rotated to directly drive register 182 the nut 341 and rack drive the secondary register 181 in unison therewith.

When the number of cancellations purchased and for which the registers have been set become exhausted that is, when the registers have descended to zero again, the meter mechanism and hence the whole machine becomes locked in a manner about to be described. It can be reset only by authorized postal authorities and this is done by inserting 125 crank 187 shown in dotted lines in Figure 4 in a squared socket 345 in the end of shaft 326 and reversing the latter to carry the nut 341 back to initial position. Of course this cannot be done against the worm gearing 324— 130

325. It is for this reason that the clutch connection 330—331 is provided. The clutch member 331 is thrown in and out between the positions shown in Figures 29 and 30 by mechanism best shown additionally in Figures 45 and 46. On the outside wall of the meter casing is a slotted bolt 346 guided on headed pins 347 and slideable in two directions under the influence of the actuating lever 348 of a key control lock 349 on the exterior of the meter casing. The key 350 (Figure 30) shown therein is the one in possession of the postal authorities. The actuator 348 operates in a cutaway portion 351 of the bolt 346 between the positions of Figures 45 and 46. The shipper 333 before described is formed on a lever 352 pivoted to the casing wall at 353. In addition to the shipper yoke 333 at the upper end thereof is a relatively angular yoke 354 that receives a pin 355 on the bolt 346. The operation of the bolt through the lock 349 thereby causes a shifting of the lever 352 that throws the clutch element 331 into and out of gear. The worm gear drive itself furnishes a sufficient lock against the resetting of the registers so that the resetting is subordinated to clutch element 331 and this can be shifted only through the post office lock 349.

30 In addition to controlling this clutch connection the bolt 346 and its actuating lock also prevents the insertion of resetting crank 187 until the lock is released. This is accomplished by a vertically movable slotted bolt 356 guided on headed pins 357 on the casing wall. An angularly turned gate portion 358 thereon normally occupies a transverse slot in bushing 328 at the end of shaft 326 as shown in Figure 45 and the socket 344 in said shaft is thereby rendered inaccessible. When the bolt 346 is actuated to unlock the mechanism an incline slot 359 therein that receives a pin 360 on bolt 356 causes the latter to rise and withdraw the gate.

45 Still another function of the bolt 346 is to lock in place a sliding cover 361 of the meter casing arranged in ways provided between flanges 362 at the upper edges of the side walls and flange 363 on the upper wall plate 343.

50 The cover is provided with lugs 364 spaced from a flange 365 at its front edge and engaging between these two is a bolt 366 formed by a flange on a slotted plate 367 guided on headed pins 368. A pin 369 on this plate extends into an inclined slot 370 on the bolt 346 so that bolt 366 goes into its normal locking position as in Figure 45 with the gate 358 and when the clutch 331 of the worm drive for the registers is thrown into gear. The screws 370 holding the top wall 343 of the meter casing in place are thus made inaccessible.

55 I have described the meter mechanism as automatically locking itself and the entire machine when the registers have run down that is, have returned to zero showing that

the cancellations paid for have become exhausted. Inasmuch as the machine and particularly the printing couple cannot function without the timing mechanism of the meter device including the cam 300—301 and the push pin 240, this locking is accomplished by locking the push pin and in the following manner:

70 The secondary register 181 makes less than one revolution to register a hundred thousand cancellations. It is provided near its periphery with a laterally projecting pin 372 (Figures 13 and 40 to 44). When the register approaches the zero mark this pin 372 reaches the position of Figure 42 at which it strikes a lever 373 pivoted at 374 to a plate 375 paralleling the outer wall of the casing and supported therefrom on studs 376. This lever 373 is pivoted at 377 to a peculiarly shaped floating link 378. Mounted on the plate 375 is a sliding bar 379 provided with headed pins 380 extending through slots in the plate (see Figure 40) which is directionally reversed from Figures 42 and 43). A spring 381 connected to a pin 382 on bar 379 which pin projects through a slot in plate 375 tends to move the bar in a direction in which an abutment 383 at one end thereof will move into a notch 384 in worm shaft 317 when said notch is properly positioned. A spring 385 connected to pivot 377 and superior to spring 381 tends to rock lever 373 to the normal position of Figure 40 in which lever 373 engages a pin 386 on bar 379 to hold it out of engagement with the said worm shaft.

75 The floating link 378 is slotted at 387 to accommodate a pin 388 on bar 379 which pin normally occupies the position at the extreme end of the slot as in Figure 40. When a register pin 372 strikes lever 373 as described, the link 378 is moved bodily to the left in Figure 42 and comes into the path of a pin 389 on the primary register wheel 182. The upper end of the link at this point is provided with a flange or shoulder 390 against which rests an ear 391 on a bell crank lever 392 pivoted to an extension 393 of the plate 375 at 394. This bell crank lever is actuated by a spring 395 connected to an extension 396 of plate 375 to turn to the right in Figure 42 and assist in this movement of the link 378 into the path of the register pin 389. The said pin, engaging the flange 390 lifts it and the link as shown in Figure 43 and it reacts upon the bell crank 392 to throw it to the position of Figure 43 so that pin 388 may move to the right and allow bar 379 to move to the right, the parts being so timed that the abutment 383 at the end of the bar moves into the notch 384 of the worm shaft which latter otherwise prevents such movement of the bar.

80 85 90 95 100 105 110 115 120 125 130 The bar 379 carries a pin 397 (see also Figure 29) that projects into the path of a yoke shaped lever 398 pivoted at 252 to the stud heretofore referred to. One arm 401 of this

lever is provided with a notch 402 with which the pin cooperates while the other arm 403 (see Figures 15, 16 and 44) is adapted to move between shoulders 247 and 250 of push pin 240 of the timing mechanism to lock the latter against projection as in Figure 14. This it does upon the movement of bar 379 and actuation by the respective register pins 372 and 389 and the meter is effectively locked so far as the projection of the push pin 240 is concerned to release the printing mechanism.

This delicate locking mechanism is provided because of the fact that the register wheels are very finely graduated and their movement on each printing operation, particularly that of the secondary register 181, is exceedingly slight.

Upon the authorized resetting of the meter by reversing the lead screw of shaft 326 with crank the tripping pin 372 passes around to the other side of lever 373 to repeat its journey. To insure completion of the movement of lever 291 when raised by push rod 275 by the envelope, said lever 291 is provided with a cam surface 399 and the pivot 309 of the eccentric strap is provided with a roller (Figure 13) which, when the eccentric strap arm 308 vibrates, engages this cam 399 and raises the lever 291 to the full extent if it has not otherwise reached that point.

Retrograde movement of the cam disk 300 is prevented by a holding pawl 404 pivoted at 405 (Figure 31) and normally occupying a position to engage the cam lug 301 if the latter recedes from its position in contact with the end of the push pin 302. The pawl is held in this position by a spring 406 connected to a bell crank arm 407 thereon and to a lug on bracket 237 to which it is pivoted.

Reference was made early in the description of the meter mechanism to the totalizer counter 183 which gives the total of all cancellations made for the life of the machine if desired. The shaft 408 thereon has an arm 409 provided with a pin 410 engaged by a forked arm 411 (Figures 31 and 33) forming part of link 314. Therefor, upon each impulse given the worm shaft 317 to drive the other registers, the counter or register 183 is actuated.

I claim as my invention:

1. In a mail printing machine, the combination with a printing couple embodying a type cylinder and a printing cylinder, of a support for the printing cylinder adapted to carry it into and out of printing contact with the type cylinder and embodying a pivoted yoke, and a spring pressed plunger acting against the yoke to normally hold the printing cylinder in such printing contact.

2. In a mail printing machine, the combination with a support, of a printing couple thereon embodying a type cylinder and a printing cylinder and a movable support for the printing cylinder adapted to carry the lat-

ter out of printing position, the type cylinder being removable and replaceable on the first mentioned support in an axial direction.

3. In a mail printing machine, the combination with a support, of a type cylinder and a case therefor embodying bearings for the cylinder, all removable as a unit from the support and replaceable therein, a printing cylinder and a movable support for the latter adapted to carry it out of printing position with reference to the type cylinder when the latter is so manipulated.

4. In a mail printing machine, the combination with a support having a socket therein, and extending therethrough, of a type cylinder and a case therefor embodying bearings for the cylinder, all removable from and replaceable in the socket as a unit, and in an axial direction, the case being supported in the socket from one end only, and driving means for the cylinder embodying a key controlled coupling element at the inner end of the case accessible from the opposite side of the support.

5. In a mail printing machine, the combination with a shaft having a printing roll and a feed roll thereon and a supporting frame, of a case having a shaft therein and bearings for the shaft, said case being supported at one end only in the support and removable therefrom in an axial direction, a type cylinder on the last mentioned shaft cooperating with the printing roll and a feed roll on said shaft cooperating with the first mentioned feed roll.

6. In a mail printing machine, the combination with a printing couple embodying a type cylinder and a printing cylinder and a shaft for each cylinder, of a drive shaft gearing between the drive shaft and the printing cylinder shaft including a shiftable gear, a swinging member carrying said shiftable gear and an inking roll mounted on the swinging member.

7. In a mail printing machine, the combination with a printing couple embodying a type cylinder and driving gear for the latter, of a swinging member for throwing said gear in and out and an inking roll carried on the swinging member.

8. In a mail printing machine, the combination with a printing couple embodying a type cylinder and driving gear for the latter, of an inking roll and a common member for throwing the cylinder in and out of gear and for carrying the inking roll toward and from the cylinder.

9. In a mail marking machine, the combination with a support and a printing couple embodying a type cylinder on one side of the support detachable in an axial direction therefrom and normally operative locking mechanism for said cylinder, of a meter for registering the operations of the type cylinder and provided with means controlling said

locking mechanism, said meter being on the other side of and independently detachable from said support and including a shaft axially alined with said type cylinder.

5 10. In a mail printing machine, the combination with a printing couple embodying a type cylinder and normally operative locking mechanism therefor, of a meter detachable independently of the printing couple for registering the operations of the type cylinder and provided with means controlling said locking mechanism, and means for driving the meter mechanism through the medium of the type cylinder.

15 11. In a mail printing machine, the combination with a printing couple embodying a type cylinder and driving mechanism therefor, of clutch elements connecting the driving mechanism with the type cylinder, a controller for the clutch elements, a stop for the controller adapted to throw out the clutch elements after each revolution of the type cylinder, a meter detachable independently of the printing couple for registering the operations 20 of the type cylinder and a device on the meter adapted to actuate the stop in timed relation to the movements of the type cylinder and meter.

25 12. In a mail printing machine, the combination with a printing couple embodying a type cylinder and driving mechanism therefor, of clutch elements connecting the driving mechanism with the type cylinder, a controller for the clutch elements having two 30 stop shoulders thereon, a stop for the controller adapted to engage one of the stop shoulders to throw out the clutch elements after each revolution of the type cylinder, a detachable meter for registering the operations of the type cylinder, a device on 35 the meter adapted to actuate the stop in timed relation to the movements of the type cylinder and meter and a latch in connection with the other stop shoulder adapted to permanently lock the controller when this stop 40 shoulder engages the stop.

45 13. In a mail printing machine, the combination with a printing couple embodying a type cylinder and driving mechanism therefor, of clutch elements connecting the driving mechanism with the type cylinder, a controller for the clutch elements having a plurality of stop shoulders thereon, a stop for the controller adapted to engage said 50 stops alternatively, there being one of the latter engaged by the stop to throw out the clutch elements after each revolution of the type cylinder, a detachable meter for registering the operations of the type cylinder, a device on the meter adapted to actuate the stop in timed relation to the movements of the type cylinder and meter and latches associated with the other stop shoulders adapted to permanently lock the controller and

type cylinder when said stop shoulders engage the stop.

55 14. In a mail printing machine, the combination with a printing couple embodying a type cylinder and driving mechanism therefor, of clutch elements connecting the driving mechanism with the type cylinder and embodying outer and inner shells and interposed jam rollers, a controller for the clutch elements projecting between the shells in a position to unseat the rollers said controller being rotatable with the type cylinder and being provided with a plurality of stop shoulders, a sliding stop pin adapted to be thrust longitudinally alternatively into the paths of different stops, there being one of the latter engaged by the stop pin to throw out the clutch elements after each revolution of the type cylinder, a detachable meter for registering the operations of the type cylinder, a device on the meter adapted to actuate the stop pin in timed relation to the movements of the type cylinder and meter and latches associated with the other stop shoulders adapted to permanently lock the controller and type cylinder when said stop shoulders engage the stop through any other timed actuation of the stop pin.

60 15. In a mail printing machine, the combination with a printing couple embodying a type cylinder and driving mechanism therefor, of clutch elements connecting the driving mechanism with the type cylinder, a controller for the clutch elements, a stop for the controller adapted to throw out the clutch elements after each revolution of the type cylinder, a support, a detachable casing on the latter carrying the type cylinder, the clutch elements and the controller as a unit, a detachable meter for registering the operations of the type cylinder and a device on the meter adapted to actuate the stop in timed relation to the movements of the type cylinder and meter.

65 16. In a mail printing machine, the combination with a printing couple embodying a type cylinder, driving mechanism therefor, and a stop for temporarily locking the type cylinder after each revolution thereof, of an independently detachable meter for registering the operations of the type cylinder and provided with means for periodically releasing said stop in timed relation to the movements of the type cylinder and meter and means for permanently locking the type 70 cylinder when said stop is released at any other time.

75 17. In a mail printing machine, the combination with a printing couple embodying a type cylinder, driving mechanism therefor, and a stop for temporarily locking the type cylinder after each revolution thereof and embodying a plunger, of a support for said elements, an independently detachable meter 80 on the support for registering the operations 85

of the type cylinder, a push pin on the meter aligned with the said stop plunger and means actuated by the meter in timed relation to the movements of the type cylinder for projecting the push pin.

18. In a mail printing machine, the combination with a printing couple embodying a type cylinder, driving mechanism therefor, and a stop for temporarily locking the type cylinder after each revolution thereof, of an independently detachable meter for registering the operations of the type cylinder and embodying a shaft, a device adapted to be projected from the meter to release the stop in timed relation to the movements of the type cylinder and meter, a spring tending to so project said device, a detent for the latter, and means adapted to be actuated by the passage of a piece of mail beneath the type cylinder for releasing the detent.

19. In a mail printing machine, the combination with a printing couple embodying a type cylinder, driving mechanism therefor, and a stop for temporarily locking the type cylinder after each revolution thereof, of an independently detachable meter for registering the operations of the type cylinder and embodying a shaft, a device adapted to be projected from the meter to release the stop in timed relation to the movements of the type cylinder and meter, a spring actuated shipper tending to so project said device, a detent for the latter, means adapted to be actuated by the passage of a piece of mail beneath the type cylinder for releasing the detent, and a cam on the meter shaft adapted to re-energize the shipper.

20. In a mail printing machine, the combination with a printing couple embodying a type cylinder, driving mechanism therefor, and a stop for temporarily locking the type cylinder after each revolution thereof, of an independently detachable meter for registering the operations of the type cylinder, a push pin adapted to be projected from the meter to release the stop in timed relation to the movements of the type cylinder and meter and having a locking shoulder thereon, a spring actuated shipper tending to so project the push pin, a detent engaging the shoulder on the latter to restrain the shipper, and means adapted to be actuated by the passage of a piece of mail beneath the type cylinder for releasing the detent.

21. In a mail printing machine, the combination with a printing couple embodying a type cylinder, driving mechanism therefor, and a stop for temporarily locking the type cylinder after each revolution thereof, of an independently detachable meter for registering the operations of the type cylinder, a push pin adapted to be projected from the meter to release the stop in timed relation to the movements of the type cylinder and meter and having a plurality of locking

shoulders thereon, a spring actuated shipper tending to so project the push pin, a detent engaging one of the locking shoulders on the latter to restrain the shipper, means adapted to be actuated by the passage of a piece of mail beneath the type cylinder for releasing the detent, and a second detent controlled by the registering mechanism of the meter and adapted to engage another locking shoulder on the push pin at a predetermined reading of the meter and permanently lock the same.

22. In a mail printing machine, the combination with a printing couple embodying a type cylinder, driving mechanism therefor and means for locking the type cylinder after each revolution thereof, of a meter detachable independently of the printing couple for registering the operations of the type cylinder, and means on the meter for periodically releasing the said locking means.

23. In a mail printing machine, the combination with a printing couple embodying a type cylinder, driving mechanism therefor and means for locking the type cylinder after each revolution thereof, of a meter detachable independently of the printing couple for registering the operations of the type cylinder, means on the meter for periodically releasing the said locking means, and means for automatically locking the releasing means when the meter register has reached a predetermined reading.

24. In a mail printing machine, the combination with a printing couple embodying a type cylinder, driving mechanism therefor and means for locking the type cylinder after each revolution thereof, of a meter detachable independently of the printing couple for registering the operations of the type cylinder, means on the meter for periodically releasing the said locking means, a register on the meter operative on a descending scale and means actuated by said register when it reaches zero for locking said releasing means.

25. In a mail printing machine, the combination with a support, a printing couple embodying a type cylinder, driving mechanism therefor and means for temporarily locking the type cylinder after each revolution thereof, of a meter case detachable from the support independently of the printing couple, and provided with an opening, a register in said case for registering the operations of the type cylinder, means adapted to be actuated by the passage of a piece of mail beneath the type cylinder for releasing the type cylinder and including a member projecting through the opening in the case and means on the support operating to render said opening accessible only when the meter is in place upon the support.

26. In a mail printing machine, the combination with a support, a printing couple embodying a type cylinder, driving mecha-

nism therefor and means for temporarily locking the type cylinder after each revolution thereof, of a meter case independently detachable from the support and provided with an opening, a register in said case for registering the operations of the type cylinder, transmission mechanism for driving said register from the printing mechanism, a stop lock therefor, means adapted to be actuated by the passage of a piece of mail beneath the type cylinder for releasing the type cylinder and the said transmission stop lock, and including a member projecting through the opening in the case, and means on the support operative to render said opening accessible only when the meter is in place upon the support.

27. In a mail printing machine, the combination with a support, a printing couple embodying a type cylinder and driving mechanism therefor, of a meter case independently detachable from the support and provided with an opening, a register in said case for registering the operations of the type cylinder, transmission mechanism for driving said register from the printing mechanism, a stop lock therefor operative upon each revolution of the printing cylinder, means adapted to be actuated by the passage of a piece of mail beneath the type cylinder for releasing the said transmission stop lock and including a member projecting through the opening in the case, and means on the support operative to render said opening accessible only when the meter is in place upon the support.

28. In a mail printing machine, the combination with a support and a printing couple embodying a type cylinder independently detachable from the support, of a key controlled lock permitting the rotation of the cylinder only when in place upon the support.

29. In a mail printing machine, the combination with a support, and a printing couple embodying a type cylinder, of a casing carrying the cylinder and its bearings and independently detachable from the support as a unit, and a key controlled lock on the casing permitting the rotation of the cylinder only when in place upon the support.

30. In a mail printing machine, the combination with a support, and a printing couple embodying a type cylinder, independently detachable from the support, of a meter for registering the operations of the type cylinder, and driving means between the cylinder and meter consisting of a lock on one of said members and a key on the other.

31. In a mail printing machine, the combination with a support and a printing couple embodying a type cylinder, of a meter for registering the operations of the type cylinder, said meter being independently detachable from the support, and driving means between the cylinder and meter consisting of a

lock on one of said members and a key on the other.

32. In a mail printing machine, the combination with a support, a casing detachably mounted on the support, a printing couple embodying a type cylinder carried by the casing, and a lock on the latter for preventing rotation of the cylinder, of a meter on the support carrying a key for said lock.

33. In a mail printing machine, the combination with a support, a casing detachably mounted on the support, a printing couple embodying a type cylinder carried by the casing, and a lock on the latter for preventing rotation of the cylinder, of a meter on the support carrying a key for said lock, and means for driving the meter from the cylinder through the medium of said key.

34. In a mail printing machine, the combination with a support, a printing couple embodying a type cylinder and a key controlled lock for the latter, of a detachable meter for registering the operations of the type cylinder and a key on the meter for the cylinder lock.

35. In a mail printing machine, the combination with a support, a printing couple embodying a type cylinder and a key controlled lock for the latter, of a detachable meter for registering the operations of the type cylinder and a key on the meter for the cylinder lock and through which the meter is driven from the type cylinder.

36. In a mail printing machine, the combination with a support, a printing couple embodying a type cylinder and a key controlled lock for the latter, of a detachable meter for registering the operations of the type cylinder and a key on the meter for the cylinder lock, said key being concealed within the meter when withdrawn from the lock.

37. In a mail printing machine, the combination with a support, a printing couple embodying a type cylinder and a key controlled lock for the latter, of a detachable meter for registering the operations of the type cylinder and a key on the meter for the cylinder lock, said key being concealed within the meter when withdrawn from the lock, and means for automatically locking the key in such concealed position when the meter is removed from the support.

38. In a mail printing machine, the combination with a support, a printing couple embodying a type cylinder, and a key controlled lock for the latter, of a detachable meter, a register therein for registering the operations of the type cylinder, a longitudinally movable shaft for the register having an exterior handle, and a key on said shaft adapted to be withdrawn from or inserted in the lock with the longitudinal movements thereof.

39. In a mail printing machine, the combination with a support, a printing couple embodying a type cylinder, and a key con-

trolled lock for the latter, of a detachable meter, a register therein for registering the operations of the type cylinder, a longitudinally movable shaft for the register having an exterior handle, a key on said shaft adapted to be withdrawn from or inserted in the lock with the longitudinal movements thereof and to be concealed within the meter when withdrawn, and means for automatically locking the shaft with the key withdrawn when the meter is removed from the support.

40. In a mail printing machine, the combination with a support, a printing couple embodying a type cylinder, and a key controlled lock for the latter, of a detachable meter, a register therein for registering the operations of the type cylinder, a longitudinally movable shaft for the register having an exterior handle, a key on said shaft adapted to be withdrawn from or inserted in the lock with the longitudinal movements thereof and to be concealed within the meter when withdrawn, and means for automatically locking the shaft with the key withdrawn when the meter is removed from the support and for releasing it when the meter is applied comprising a key post on the support, an actuator adapted to cooperate therewith and a rotary device on the shaft interlocking there-
30 with except when the actuator and key post are cooperating.

41. In a mail printing machine, the combination with a support, a printing couple embodying a type cylinder and a key controlled lock for the latter, of a detachable meter for registering the operations of the type cylinder, a key on the meter for the cylinder lock, said key being concealed within the meter when withdrawn from the lock, and means actuated through the removal of the meter from the support for locking the key in such concealed position.

42. In a mail printing machine, the combination with a support, a printing couple embodying a type cylinder and a key controlled lock for the latter, of a detachable meter for registering the operations of the type cylinder, a key on the meter for the cylinder lock, said key being concealed within the meter when withdrawn from the lock, means on the meter for locking the key in such concealed position, a key on the support adapted to release said locking means when the meter is in position and an automatic device rendering said key locking means inaccessible when removed from the key on the support.

43. In a mail printing machine, the combination with a printing couple embodying a type cylinder, of a meter for keeping account of the operations of the type cylinder embodying a register, a pinion on the register, a screw driven from the type cylinder, a nut thereon, and a rack carried by the nut and meshing with the pinion.

44. In a mail printing machine, the combi-

nation with a printing couple embodying a type cylinder, of a meter for keeping account of the operations of the type cylinder embodying a register, a pinion on the register, a screw, a worm drive from the type cylinder to the screw, a nut on the latter, and a rack carried by the nut and meshing with the pinion.

45. In a mail printing machine, the combination with a printing couple embodying a type cylinder, of a meter for keeping account of the operations of the type cylinder embodying a register, a worm drive from the type cylinder to the register and a clutch between the latter and the worm to permit re-setting the register.

46. In a mail printing machine, the combination with a printing couple embodying a type cylinder, of a meter for keeping account of the operations of the type cylinder embodying a register, a worm drive from the type cylinder to the register, a clutch between the latter and the worm to permit re-setting the register and key controlled means for operating the clutch.
